UNITED STATES PATENT OFFICE.

RALPH B. WAITE, OF SPRINGVILLE, NEW YORK.

COMBINATION-LOCK FOR UMBRELLAS.

SPECIFICATION forming part of Letters Patent No. 752,489, dated February 16, 1904.

Application filed May 9, 1903. Serial No. 156,494. (No model.)

To all whom it may concern:

Be it known that I, RALPH B. WAITE, a citizen of the United States, and a resident of Springville, in the county of Erie and State of New York, have invented new and useful Improvements in Combination-Locks for Umbrellas, of which the following is a full, clear, and exact description.

This invention relates to certain novel and useful improvements in combination-locks particularly applicable to umbrellas and the like.

It is the object of my invention to provide a device which when placed upon the umbrella-handle will incase the spring-latch therein and prevent the umbrella being opened by parties not familiar with the combination of the lock.

A further object of my invention is to provide a simple combination-lock which will render it possible for one familiar with the working thereof to open the umbrella in the dark, the proper combination of the lock being recognized by a number of clicking sounds caused by contact of certain portions of the lock when turned or operated.

A further object of the invention is to provide a simple and inexpensive combination-lock which may be applied to any umbrella.

With the above-recited objects and others of a similar nature in view the invention consists in the construction, combination, and arrangement of parts, as is described in this specification, delineated in the accompanying drawings, and set forth in the appended claims.

Reference is to be had to the accompanying drawings, forming a part of this specification, in which similar characters of reference indicate corresponding parts in all the figures.

Figure 1 is a view, partly in elevation and partly in section, showing my improved device in its closed or locking position. Fig. 2 is a similar view, but showing the lock after it has been released to permit the opening of the umbrella. Fig. 3 is a transverse sectional view taken on the line 3 3 of Fig. 2. Fig. 4 is a similar view taken on the line 4 4 of Fig. 2. Fig. 5 is a cross-sectional view taken on the line 5 5 of Fig. 2. Fig. 6 is a

detail perspective view of the upper portion 50 of the lock-casing, and Figs. 7, 8, 9, and 10 are detail views of portions of the locking rings or disks.

Referring now to the accompanying drawings in detail, A designates the rod-staff of 55 an ordinary umbrella, having inserted therein a well-known form of catch or locking-spring B. Slidably mounted upon the staff or rod of the umbrella is a tubular runner-sleeve 5, having therein an elongated slot 6, 60 adapted to permit the latch-spring B to protrude therethrough when the umbrella is in its closed position, the aforesaid tubular runner-sleeve 5 carrying at its upper end a collar 7, provided with notches 8 for the seating 65 of the lower ends of the umbrella-stretchers 9.

I will now proceed to describe in detail my improved combination-lock, which is adapted to fit over and incase the locking-spring B, thereby preventing the latter from being operated by direct manual contact or by other means.

My lock comprises, essentially, a tubular casing 10, having in its upper end portion a circumferential indentation or inwardly-formed 75 flange 11, the extreme upper end of the casing 10 having a cap or covering 12, adapted to be soldered, riveted, or otherwise suitably secured after the interior mechanism of the lock has been assembled in said casing. The 80 lower portion of the casing is formed with a reduced or round end portion 13, which terminates in a downwardly-extending flange 14, adapted to bear lightly against the sleeve 5. It is to be noted in this connection that the 85 lower end of the sleeve 5 is provided with a retaining flange or shoulder 15, which prevents the casing of the sleeve from sliding over the latch B and down to the handle portion of the umbrella, thereby exposing the 90 aforesaid latch.

Within the upper portion of the casing—that is, the portion between the indented flange 11 and the top of the cap—is inserted the locking mechanism proper of the device, 95 the detail parts of which I have shown in Figs. 7, 8, 9, and 10, such locking mechanism comprising a series of superposed annular disks

having notches arranged therein, these disks being rotatable relative to each other in such manner that the notches may be brought into alinement to permit a passage therethrough 5 of the locking-key 16, projecting from the runner-sleeve 5. The lowermost disk of the series, which is shown in detail in Fig. 10, I have designated by the numeral 17, said disk having secured to its under surface a curved 10 spring 18, adapted to frictionally hold the annular disk 17 in its proper position when said disk is set. The upper surface of the disk 17 is provided with a segmental groove 19 and has also a vertically arranged recess 20. 15 Adapted to rest upon this disk 17 is an annular washer or disk, such as shown at 21, said disk having a recess or notch 22 similar to the notch or recess 20 and a pin 23, which pin is adapted to lie within and move around the slot 20 or groove 19 of the disk 17 when the parts are turned relative to each other. A split bearing-ring, such as shown at 24, is placed upon the upper surface of the disk 21, which prevents a third annular locking ring or disk 25 25 being disturbed or affected by the movement of the lower disks, the disk 25 being superposed upon this ring, the last-mentioned member 25 having a recess 26 similar to the recesses 20 and 22, the periphery of this member 30 25 being provided with any suitable number of notches spaced apart, such notches being shown at 27. When the parts are assembled in their operative position, the notches 27 are adapted to seat the inwardly-extending head 35 or projection 28, formed at the end of the spring-arm 29, which spring-arm is preferably cut from the metal of the top portion of the sleeve.

From the above description, taken in connection with the accompanying drawings, the construction and operation of my improved locking device will be readily apparent. As mentioned above, the device is intended to lock an umbrella when the latter is closed by 40 the runner-sleeve 5 engaging the spring-catch B in the staff, said spring being covered by the casing 10, which prevents the spring from being uncaught or released except when the combination-disks are set so that the recesses 45 20, 22, and 26 are in alinement or register, which will then permit the lock or casing to slide over the key 16 on the sleeve. This may be accomplished by turning the casing a certain and predetermined number of clicks 50 or steps in one direction, each step comprising the advancement of the head portion 28 from one notch 27 to an adjacent one. This will bring the recess in the upper ring-like member 25 in line with the key of the runner, 55 60 which key will then rest upon the subjacent disk. By turning the sleeve in the opposite direction a certain number of clicks the opening or recess 22 in the disk 21 when the latter is rotated will also be brought into aline-

ment of the key or runner, and as the lower- 65 most disk 17 has its recess 20 held in alinement with the recess 22 the key 16 will pass through all of the alining recesses and the opening in the split ring 24. The casing may then be pushed upward, the lower reduced 70 curved end portion 13 pressing down the spring on the staff, which will permit the umbrella to be raised. The number of clicks made by the head 28 coming into contact with the notches 27 is intended to designate the 75 combination, as one familiar with the same will know that by turning the lock until a certain number of clicks have been heard the umbrella may be raised, this being especially 80 advantageous, as the umbrella may be unlocked in the dark. Any number of notches may be provided on this clicking disk, and it is to be noted that the combination may also be changed by changing the position of the contact-pin 23 in the disk 21 and also by 85 lengthening the slot in the disk 17.

While I have shown and herein described one particular embodiment of my invention, it is of course to be understood that I do not limit myself to the precise details of construction shown herein, as there may be modifications and variations in certain respects without departing from the essential features of the invention or sacrificing any of the advantages thereof.

Having thus described my invention, I claim as new and desire to secure by Letters Patent—

1. The combination with a rod having a spring-latch, and a runner-sleeve having a projecting key thereon, of a casing rotatably mounted on the runner-sleeve, said casing enclosing the latch when the umbrella is in its closed position, and a plurality of rotatable annular disks mounted within the casing, said disks having recesses therein, which when 105 brought into vertical alinement permit the passage of the key on the sleeve, whereby the umbrella may be raised by a portion of the casing depressing the spring-latch, substantially as set forth.

2. The combination with an umbrella, and a runner-sleeve therefor, said sleeve having a key thereon, of a lock comprising a casing, a plurality of movable annular disks within said casing, said disks having recesses adapted to 110 be brought into alinement to form a passage for the key on the sleeve, whereby the casing may be moved upward on the sleeve to permit the raising of the umbrella, substantially as set forth.

3. The combination with an umbrella, and a runner-sleeve, said sleeve having a key thereon, of means adapted to depress a spring in the rod of the umbrella and permit the raising of the latter, said means comprising a casing, a plurality of superposed recessed disks therein, the recesses of the disks being adapted to be brought into alinement, the upper

most of said disks having a series of notches in its periphery, and a spring-arm on the casing adapted to engage the notches in the disk as the casing is revolved, substantially as set forth.

4. The combination with an umbrella, and a runner-sleeve having a projecting key thereon, of means adapted to depress a spring in the umbrella-rod and permit the umbrella to be raised, said lock comprising a revoluble casing surrounding the spring on the rod when the umbrella is closed, said casing having a tapered curved end portion designed to bear upon the spring in the umbrella-rod, a plurality of superposed recessed locking-disks in said casing, the lowermost disk having a groove in the upper surface thereof, a retaining-spring

secured to the under side of the disk, a pin in the superposed contacting disk, projecting into the groove, a ring on the second-mentioned disk, and an upper notched disk mounted on said ring, the construction being such that when the recesses of the disks are in alignment for the passage of the key on the runner, the casing may be moved upward to depress the spring on the rod, substantially as set forth. 20

In testimony whereof I have signed my name to this specification in the presence of two subscribing witnesses.

RALPH B. WAITE.
